UNITED STATES PATENT OFFICE.

FRANK A. YOUNG, OF SYRACUSE, NEW YORK, ASSIGNOR TO THE MONARCH TYPEWRITER COMPANY, OF SYRACUSE, NEW YORK, A CORPORATION OF NEW JERSEY.

TYPE-WRITING MACHINE.

No. 904,170.

Specification of Letters Patent.

Patented Nov. 17, 1906.

Application filed October 15, 1906. Serial No. 339,060.

To all whom it may concern:

Be it known that I, FRANK A. YOUNG, citizen of the United States, and resident of Syracuse, in the county of Onondaga and State of New York, have invented certain new and useful Improvements in Type-Writing Machines, of which the following is a specification.

My invention relates more especially to 10 ribbon mechanism for typewriting machines and has for its main object the provision of improved means whereby a ribbon normally removed from the printing point and having a plurality of fields of different characteristics may be so controlled that when the 15 printing keys are actuated it may be moved to cover the printing point with any desired field.

Although particularly adapted to the object stated, my invention may, nevertheless, 20 be used to advantage with ribbons of uniform character throughout in order to thoroughly exhaust such ribbons by writing on them in more than one longitudinal line.

To the above and other ends the invention 25 consists in the features of construction, combinations of devices and arrangements of parts hereinafter fully described and particularly pointed out in the claims.

The invention is shown as applied to a 30 Monarch typewriter but it is to be understood that said invention may be adapted to other forms of writing machines.

In carrying out my invention in the present instance I substitute for the usual vibratory operating lever of the Monarch machine (which lever has a fixed fulcrum) an operating lever which is fulcrumed on an adjustable supporting lever, and provide 40 hand-actuated means for controlling said supporting lever so as to vary the normal position of the operating lever and its fulcrum. The operating lever is pivotally connected with a link which is part of the 45 vibrator actuating mechanism but the arrangement is such that the shifting of the operating lever from one normal position to another does not affect the link nor the rest of the actuating mechanism. Furthermore, 50 the construction and arrangement of the supporting lever and its controlling means is such that the bodily shift of the operating lever is effected readily and with the expenditure of a comparatively small amount of 55 power and said operating lever is maintained

with certainty in either of the positions in which it may be set.

In the accompanying drawings, Figure 1 is a vertical longitudinal sectional view of a typewriting machine embodying my invention, parts of the machine being omitted. 60 Fig. 2 is a transverse vertical sectional view of the machine taken on a plane forward of the top plate, parts being omitted and parts being broken away. Fig. 3 is an enlarged 65 fragmentary side sectional view illustrating more particularly the operating lever, its supporting lever and the means for controlling or adjusting said supporting lever to shift the operating lever.

In the drawings, 1 designates the base of the machine from which rise corner posts 2 supporting a top plate 3. Key levers 4 are fulcrumed on a fulcrum plate 5 at the rear of the base. Each key lever is provided with a restoring spring 6 and has pivoted to it at 7 a sub-lever 8, the lower end whereof is slotted to coöperate with a fulcrum bar 9 and the upper end whereof is connected by a link 10 with a type bar 11. The type bars are pivoted in hangers 12 arranged in segmental series on a segmental type bar support 13. Said type bars are normally supported at their free end portions on a type rest 14 and are adapted, when their associate key levers 80 are actuated, to coöperate with the front face of a platen 15 mounted in a carriage comprising side bars 16 joined at the rear by a slide bar 17, the latter being grooved at its top and bottom to coöperate with anti-friction balls 90 18. Said balls also coöperate with grooved guide rails 19 which are fixed to standards 20 rising from the top plate. The platen carriage carries a feed rack 21 which normally meshes with a feed pinion 22, the latter being 95 operatively connected with a toothed escapement wheel 23. Coöoperative with said escapement wheel are escapement dogs 24 mounted at the top of a pivoted vibratory 100 dog carrier or rocker 25 having a horizontally disposed arm 26 which is connected by a link 27 with an arm 28 extending centrally and rearwardly from a rock shaft 29 pivoted on screw pivots 30 secured in the sides of the base. The arm 28 and rock shaft 29 are part 105 of a universal bar frame, the latter comprising, in addition, side arms 31 extending rearwardly from the rock shaft 29 near its ends, and a universal bar proper 32 connecting said side arms and the central arms 28 and 110

extending from side to side of the machine beneath the key levers 4. When one of the latter is operated the universal bar frame is swung downwardly on its pivots, causing the escapement or letter feeding devices to coöperate in a known manner to permit the carriage to be drawn a letter space distance to the left under the influence of a spring drum 33 with which said carriage is connected by 10 a band or strap 34.

A ribbon 35 is wound upon a pair of spools 36 one disposed at each side of the machine forwardly of the platen and above the top plate. As herein shown the ribbon is divided 15 into longitudinal stripes or fields *a* and *b* of different characteristics, that is to say, the field *a* may be of one color such as black and the field *b* of another color such as red, for example; or the field *a* may be record ribbon 20 and the field *b* copying ribbon. The ribbon may be fed longitudinally back and forth between the spools by any suitable ribbon feeding mechanism, that shown in the drawings being the usual mechanism of the Mon- 25 arch machine and comprising for each ribbon spool a small beveled gear 37 operatively connected with the spool and meshing with a beveled pinion 38 at the forward end of a horizontal shaft 39, said shaft carrying at its 30 rear end a beveled pinion 40. Each pinion 40 is adapted to mesh with a driving pinion 41 fixed to a horizontal driving shaft 42 extending from side to side of the machine. The driving shaft is connected with and re- 35 ceives motion from the spring drum 33, the connections comprising two beveled gears 43 and 44, the gear 43 being operatively connected with the spring drum and the gear 44 with the driving shaft 42 in such a way that 40 while said gear 44 and said shaft always turn together, yet said shaft may be moved endwise relatively to said gear. The end- 45 wise movement of the driving shaft serves to connect one or the other of the driving pinions 41 with its associate pinion 40 and to cause one or the other of the ribbon spools to be turned to wind the ribbon thereon in the usual manner.

That portion of the ribbon which extends 50 between the ribbon spools is normally held or maintained below the printing point *c* at the front of the platen by a vibratory ribbon carrier or vibrator 45 which is guided and supported in the upright arms 46 of a 55 guide bracket 47 secured by screws 48 to the top plate. The lower end or stem of the vibrator is slotted and provided with a cross pin 49 which coöperates with the slotted forward end of an operating lever 60 50. In the present instance the lever 50 is fulcrumed on a rivet 51 which is carried at the forward end portion of the horizontal arm 52 of an angular supporting lever 53 which is pivoted at 54 in a lug 55 depend- 65 ing from the top plate. The supporting

lever 53 is substantially right angled, its shorter arm 52 being horizontally disposed while its longer arm 56 depends from the pivot 54 in a substantially vertical direction. The rear arm of the operating lever 50 is 70 pivotally connected at 57 with the upper end portion of an actuating link 58, the lower end whereof is pivotally connected at 59 with the central arm 28 of the universal bar frame. 75

The position of the supporting lever 53 may be adjusted in order to vary or shift the position of the fulcrum 51 of the operating lever and the devices which I prefer to employ for adjusting and controlling said 80 supporting lever 53 will now be described. The lower end of the depending arm 56 of the supporting lever 53 is formed with a slot 60 engaging which is a grooved pin or member 61 carried at the lower end of a 85 crank arm 62, said crank arm, as will be best seen in Fig. 2, being provided at its upper end with a collar 63 which is suitably secured at the right-hand end of a horizontally disposed rock shaft 64. The rock shaft extends transversely of the machine from about 90 its middle towards the left-hand side thereof and is supported in bearing openings formed in the rearwardly extending ears 65 of a long bearing bracket 66, the latter being secured by headed screws 67 to the back of the upturned lip 68 of a stop bar 69 which is U-shaped as seen from above, the side arms 70 of the bar being secured by headed screws 71 to posts 72 rising from the base 1. 100 The stop bar 69 is part of the subject-matter of a separate application filed by me July 22, 1904, Serial No. 217,607, and is not claimed herein. The collar 63 of the right-hand crank arm 62 is secured to the 105 end portion of the rock-shaft 64 outside the right-hand supporting ear 65. The left-hand end portion of the rock shaft 64 likewise extends beyond or outside of the left-hand bracket ear 65 as shown in Fig. 2 and has fixed to it a collar portion 73 of a crank arm 74 which extends upwardly from the rock shaft. The crank arms 74 and 62 serve 110 in effect as the arms of a single lever of which the rock shaft 64 is the elongated 115 pivot or fulcrum. Pivotally connected at 75 to the upper end of the crank or lever arm 74 is a bar 76 horizontally disposed and extending towards the front of the machine. The rear portion of the bar 76 is upright as 120 shown in Figs. 1 and 3 but the bar is given a quarter turn as indicated at 77, so that the front portion thereof is horizontal and extends through a horizontal opening or slot 78 in the front plate 79 of the machine. 125 Near its forward end at 80 the bar 76 is shouldered to provide a stop or catch. Secured to the end of the bar 76 in front of the front plate is a finger button or cap 81 by which the bar and the mechanism that 130

actuates it may be conveniently controlled. An angled spring 82 is secured at the rear of the front plate 79 by headed screws 83. The horizontal portion of the spring 82 lies beneath the horizontal forward portion of the bar 76 and serves to maintain the latter in contact with the upper edge of the slot 78 in the front plate.

Referring now to the operation of the mechanism hereinbefore described and assuming that the parts are normally positioned as illustrated in full lines in Figs. 1 and 3, it will be understood that when any of the printing key levers 4 are suitably actuated the universal bar frame will be swung downwardly, drawing the actuating link 58 longitudinally downward and swinging the operating lever 50 on its fulcrum 51 to cause the vibrator to be thrown upward. The parts are so proportioned that at this time this upward throw of the vibrator will continue until the operating lever has reached the dotted line position indicated by the reference character 50' in Fig. 3 and the ribbon has been moved upwardly far enough to bring its upper field *a* opposite the printing point. The parts will be restored to normal position by gravity and the usual universal bar spring (not shown). As long as the parts are normally positioned as shown by the full lines in Fig. 3 the throw of the vibrator will be constant and the points at which its upward movement begins and ends will be the same so that the type impressions will follow in a path along the upper field *a* of the ribbon and longitudinally thereof.

When it is desired to make use of the lower field *b* of the ribbon the operator exerts a rearward pressure against the button 81 moving the bar 76 rearwardly and, by means of the crank arm 74, rock shaft 64 and crank arm 62, swinging the arm 56 of the supporting lever 53 forwardly and the arm 52 of said lever upwardly. The upward movement of the arm 52 moves the fulcrum 51 upwardly, said fulcrum acting on the operating lever 50 and swinging or lifting it upwardly about the pivotal connection 57 as a center without disturbing the actuating link 58 or the other members of the train of ribbon actuating devices. As the bar 76 is pushed rearwardly the upper face of its forward portion is maintained in contact with the upper edge of the slot 78 by the spring 82; and when the shoulder 80 on said bar has passed entirely through said slot the spring 82 operates to lift the forward end portion of the bar 76 and to carry the shoulder 80 higher than the opening or slot 78, so that if thereafter the button 81 be released any tendency of the bar 76 to return to the position from which it started will be prevented by the shoulder 80 contacting with that portion of the rear face of the front plate 79 immediately above the slot 78. In

other words, the shoulder 80 serves as a detent or lock to maintain the bar 76 and the parts controlled thereby set in their newly adjusted positions. When the bar 76 has been pushed rearwardly and locked by the shoulder 80, the fulcrum 51 of the operating lever will have been raised from the full line position shown in Fig. 3 to the dotted line position shown in said figure, and the operating lever itself will have been raised to, and will be normally maintained in, the dotted line position designated as 50^a in said Fig. 3, the normal position of the link 58, however, remaining the same in both cases. At each actuation of the universal bar frame 80 the link 58 will operate on the lever 50 to swing it from the normal dotted-line position 50^a to the dotted line position indicated by 50^b in Fig. 3. When the operating lever is in the last named position the vibratory ribbon carrier will have been lifted far enough to bring the lower field *b* of the ribbon opposite the printing point when a printing key is actuated. Consequently, the type impressions will follow in a path along and longitudinally of the lower field or portion *b* of the ribbon.

When it may be again desired to make use of the upper field *a* of the ribbon the operator first presses down on the top of the finger piece or button 81, thereby flexing the spring 82 and bringing the shoulder 80 on the arm 76 opposite or in register with the slot 78 in the front plate. Thereafter, through the influence of gravity the parts 100 will be restored to the position shown in full lines in Fig. 3, being maintained in that position by the engagement of the crank arm 74 with a stop which may be in the form of an extension or lip 84 bent laterally outward 105 horizontally from the top of the left-hand ear 65 of the supporting bracket 66.

Various changes may be made without departing from the spirit and scope of my invention.

What I claim as new and desire to secure by Letters Patent, is:—

1. In a typewriting machine, the combination of a vibratory ribbon carrier, an operating lever therefor, means for actuating the same, a supporting lever pivoted between its ends to a fixed part and providing on one of its arms a fulcrum for the operating lever, the arms of said lever being unvarying in length, and means connected with the other 120 arm of said lever for actuating it to shift the normal position of the operating lever and ribbon carrier, said first recited means providing a fulcrum on which said operating lever is shifted to change its normal 125 position.

2. In a typewriting machine, the combination of a vibratory ribbon carrier, an operating lever therefor, means for actuating the same, an angular supporting lever hav- 130

ing a horizontally disposed arm and a vertically disposed arm, said arms being unvarying in length, said operating lever being fulcrumed on the horizontally disposed arm 5 of said angular supporting lever, and means connected with the other arm of said supporting lever for actuating it to shift the normal position of the operating lever and ribbon carrier, said first recited means providing a fulcrum on which said operating 10 lever is shifted to change its normal position.

3. In a typewriting machine, the combination of a vibratory ribbon carrier, an operating lever therefor, a key actuated universal bar, a link between said universal bar and said operating lever, a supporting lever pivoted between its ends and providing on one of its arms a fulcrum for the operating lever, the arms of said lever being unvarying in length, and means connected 15 with the other arm of said supporting lever for actuating it to shift the normal position of the operating lever and ribbon carrier, said link providing a fulcrum on which said operating lever is shifted to change its normal 20 position.

4. In a typewriting machine, the combination of a vibratory ribbon carrier, an operating lever therefor, a key actuated universal bar, a link connecting said universal bar with said operating lever, an angular supporting lever having a horizontally disposed arm and a vertically disposed arm, said arms being unvarying in length, the operating lever being fulcrumed on the horizontally disposed arm of said supporting lever, and means connected with the other arm of said supporting lever for actuating it to shift the normal position of the operating lever and ribbon carrier, said link providing a fulcrum on which said operating lever is shifted to change its normal 35 position.

5. In a typewriting machine, the combination of a vibratory ribbon carrier, an operating lever therefor, means for actuating the same, a supporting lever pivoted between its ends to a fixed part and providing on one of its arms a fulcrum for the operating lever, the arms of said lever being unvarying in length, and means connected with the other arm of said lever for actuating it to shift the normal position of the operating lever and ribbon carrier, said last recited means comprising a lever having an elongated pivot or fulcrum, and a hand actuated arm connected with said lever, said first recited means providing a fulcrum on which said operating lever is shifted to change its normal 50 position.

6. In a typewriting machine, the combination of a vibratory ribbon carrier, an operating lever therefor, means for actuating the same, a supporting lever pivoted between its ends and providing on one of its arms a ful- 55

crum for the operating lever, and means connected with the other arm of said supporting lever for actuating it to shift the normal position of the operating lever and ribbon carrier, said last named means comprising a lever having an elongated pivot or fulcrum, and a hand actuated bar connected with said lever, said bar extending through an opening or slot in the front plate of the machine and being off-set to provide a latch for maintaining the supporting lever in one of the positions in which it may be adjusted. 75

7. In a typewriting machine, the combination of a vibratory ribbon carrier, an operating lever therefor, means for actuating the same, a supporting lever pivoted between its ends and providing on one of its arms a fulcrum for the operating lever, and means connected with the other arm of said lever for actuating it to shift the normal position of the operating lever and ribbon vibrator, said last named means comprising a pair of crank arms connected by a rock shaft, and a bar or member provided with a finger piece at the front of the machine. 90

8. In a typewriting machine, the combination of a vibratory ribbon carrier, an operating lever therefor, means for actuating the same, an angular supporting lever having a horizontally disposed arm and a vertically disposed arm, said operating lever being fulcrumed on the horizontally disposed arm of said angular supporting lever, and means connected with the other arm of said supporting lever for actuating it to shift the normal position of the operating lever and ribbon carrier, said last recited means comprising a rock shaft having a crank arm connected with said supporting lever, said rock shaft having a second crank arm and a finger controlled member or bar connected with said second crank arm. 100

9. In a typewriting machine, the combination of a vibratory ribbon carrier, an operating lever therefor, a key actuated universal bar, a link between said universal bar and said operating lever, a supporting lever pivoted between its ends and providing on one of its arms a fulcrum for the operating lever, and means connected with the other arm of said supporting lever for actuating it to shift the normal position of the operating lever and ribbon carrier, said last recited means comprising a rock shaft rigidly supporting two crank arms, one of which is connected with said supporting lever and the other of which is connected with a finger controlled member or bar operative from the front of the machine. 110

10. In a typewriting machine, the combination of a vibratory ribbon carrier, an operating lever therefor, a key actuated universal bar, a link connecting said universal bar with said operating lever, an angular supporting lever having a horizontally disposed 120

Correction in Letters Patent No. 904,170.

904,170

5 arm and a vertically disposed arm, the operating lever being fulcrumed on the horizontally disposed arm of said supporting lever, and means connected with the other arm of said supporting lever for actuating it to shift the normal position of the operating lever and ribbon carrier, said last recited means comprising a rock shaft rigidly supporting two crank arms, one of which is connected to

an arm having a finger piece operative from 10 the front of the machine.
